UNITED STATES PATENT OFFICE.

HENRY L. BRADLEY, OF NEW HAVEN, AND FREDERIC W. OTIS, OF ORANGE, CONNECTICUT; SAID OTIS ASSIGNOR TO SAID BRADLEY.

TINNING-MACHINE.

SPECIFICATION forming part of Letters Patent No. 746,000, dated December 8, 1903.

Application filed April 24, 1903. Serial No. 154,055. (No model.)

To all whom it may concern:

Be it known that we, HENRY L. BRADLEY, residing at New Haven, and FREDERIC W. OTIS, residing at Orange, county of New Haven, State of Connecticut, citizens of the United States, have invented a new and useful Tinning-Machine, of which the following is a specification.

This invention relates to the "tinning," so called—that is, the plating with tin—of small metallic articles.

Heretofore, so far as we are aware, articles have been tinned by hand-labor, no machines having been placed upon the market that would perform the operation successfully. In tinning articles by the present method the operator uses a pair of tongs, with which he grips each individual article, plunges it into molten tin, and then shakes it two or three times with great force in order to throw off the surplus tin and leave a smooth surface. The article is then laid on a revolving table and subjected to an air-blast to cool it and set the tin. This method of tinning articles is slow, wasteful, and necessarily expensive. As it is necessary to keep quite a large quantity of tin in a molten condition, requiring the consumption of considerable fuel, it is desirable that the articles be handled as rapidly as possible. In doing this the operators quickly become physically tired from shaking the articles to remove the surplus tin, with the result that a much larger amount of tin remains on the articles than is necessary or desirable, thus causing a constant waste of tin. Another serious difficulty is the constant danger of the operator being burned by the tin, as it is not practicable to use any guard on the tongs other than an ordinary glove. It will be obvious, furthermore, that this hand operation of tinning is necessarily relatively slow, no matter how ineffectually the shaking operation may be performed.

It is one of the objects of this invention to provide a tinning machine having a pair of jaws that will grip the article and hold it during the dipping operation and will then whirl it while gripped by the jaws, thus utilizing the principle of centrifugal force to remove the surplus tin.

It is a further object of the invention to

provide a tinning-machine so constructed that during the dipping operation the jaws will be wholly disconnected from the driving mechanism, thereby avoiding the possibility of accident from the whirling motion being imparted to the jaws before they are withdrawn from the molten tin. 55

It is a further object of the invention to provide a tinning-machine so constructed 60 that the upward movement of the jaws after the dipping operation shall set the machine in motion.

It is a further object of the invention to provide a tinning-machine so constructed 65 that when set in motion by the upward movement of the jaws as they are withdrawn from the molten tin the driving mechanism will impart to the jaws a certain number of revolutions and will stop with the jaws in the starting position. 70

It is a further object of the invention to provide a tinning-machine having a receptacle under the jaws which will catch a tinned article as it drops from the jaws when they 75 are opened and will expel the tinned article therefrom when the jaws are given a downward turn preparatory to plunging another article into the molten tin.

It is a further object of the invention to 80 provide a tinning-machine having jaws which hold an article while being dipped into molten tin and are then whirled to remove the surplus tin with a hood or guard within which the jaws revolve and which will catch all of 85 the flying tin, thus avoiding waste of tin and also avoiding danger to the operator and to other persons and surrounding objects from the flying tin.

With these and other objects in view the invention consists in certain constructions and in certain parts, improvements, and combinations, which will be hereinafter described and then specifically pointed out in the claims hereunto appended. 90

In the accompanying drawings, forming 95 part of this specification, in which like characters of reference indicate the same parts, Figure 1 is a plan view of the machine complete, the top of the hood being removed and the jaws in the gripping position; Fig. 2, a side elevation, the hood being in vertical sec-

tion; Fig. 3, a detail sectional view illustrating a portion of the clutch-releasing mechanism, the shoe being in its normal or raised position, as in Fig. 2, and the bell-crank lever having commenced to swing downward as in withdrawing the shoe to release the sliding dog; Fig. 4, a similar view amplified, showing the position of the parts at the instant the shoe is released; Fig. 5, a detail sectional view showing the parts of the divided shaft in the disconnected or broken position as during the dipping operation; Fig. 6, a similar view showing said parts connected as during the whirling operation; Fig. 7, a detail sectional view showing the construction and operation of the jaws which are in the open position, as when a tinned article has been dropped and the jaws are ready to receive another article to be operated upon; and Fig. 8 is a detail sectional view on the line indicated by 8 in Fig. 1, illustrating a form of brake which may be used to check the rotation of the divided shaft.

20 denotes the bed, within which is a trough 21 for molten tin, the trough being covered by a suitably-shaped hood 22, having an opening 93.

23 denotes framework rigidly secured to the bed, which supports a stud 24, on which a belt-pulley 25 and a gear-wheel 26 are mounted to turn independently.

27 and 28 denote the two parts of a divided shaft which carries the article-holder, (designated as a whole by 29.) Part 27 of the shaft 35 is mounted to turn in the framework and has a longitudinal bore in which a rod 32 is adapted to reciprocate, the outer end of said rod projecting under the rim of the belt-pulley, as indicated by dotted lines in Fig. 2.

30 denotes a pinion which meshes with gear-wheel 26 and is secured to part 27 of the shaft, so as to drive the two-part shaft.

31 denotes a collar at the inner end of part 27.

45 The inner end of rod 32 bears against the end of part 28, as clearly shown in Figs. 5 and 6. Part 28 of the shaft is journaled in an arm 33, which is hinged, as at 34, to a bracket 35, itself rigidly secured to the bed. 50 At the inner end of part 28 is a collar 36, which is rigidly secured thereto.

37 (see Figs. 5 and 6) denotes a spring-controlled locking-pin, which is socketed in collar 31 and the forward end of which engages a recess 38 in collar 36, thereby locking the two parts of the divided shaft together, as clearly shown in Fig. 6, so that part 27 will drive part 28 when said parts are in alinement.

It will be obvious from Fig. 2 that arm 33, carrying part 28 of the shaft, can only swing downward. Consequently the shaft can only break downward. It will be noted, furthermore, that when the shaft is broken, as in Fig. 5 and in dotted lines in Fig. 2, there is 65 no connection whatever between the two parts of the shaft, so that even should the machine be started and rotary movement be

communicated to part 27 it would have no effect whatever upon part 28, and the operator would be perfectly safe from any danger 70 of having the jaws rotated while submerged in the molten tin. We furthermore insure that the shaft can only be broken when the jaws are swung downward into vertical—that is, the dipping—position. This is effected 75 by making recess 38 in collar 36 and the forward end of locking-pin 37 straight upon the lower side and making both of said parts upon the upper side an arc-shaped curve, of which pivotal point 34 is the center, said 80 curve upon the locking-pin being indicated by 94. This construction permits the shaft to break readily when the parts are in the position shown in Fig. 5 and indicated in dotted lines in Fig. 2, but in no other position, as 85 the pin will bind in the recess and lock the parts of the shaft in alinement, except when locking-pin 37 and the corresponding recess are in a predetermined position—as, for example, when collars 31 and 36 are in such a 90 position as to place said locking-pin and recess directly under sliding rod 32, as in Fig. 5. This is a matter of importance, as it renders it impossible for the shaft to break either by accident or otherwise except when the 95 shaft is stationary and in one position only—that is, with the jaws in the dipping position.

39 (see dotted lines, Fig. 2) denotes a spring-actuated pin socketed in bracket 35 and engaging a knuckle 40 on arm 33—i. e., the hinge member of said arm—in such a manner as to throw part 27 of the shaft upward to the normal or operative position, as in Figs. 1, 2, and 6, after said parts have been separated, as in Fig. 5, or, as we term it for convenience, 105 the shaft has been broken.

The hub 41 of article-holder 29 is rigidly secured to the outer end of part 28 of the divided shaft. The construction of the holder will be readily understood from Fig. 7, which see in connection with Fig. 1. 42 denotes the jaws, which are pivoted to a cross-piece 43, carried by a rod 44, which passes through a carrier 45, itself rigidly secured in hub 41. The forward end of the carrier is beveled, as 110 at 46, and is engaged by the rear ends of the jaws. A spring 47 within the carrier, bearing against shoulders on the carrier and on the rod, acts to retract the rod and, through the engagement of the rear ends of the jaws with 115 the beveled end of the carrier, to force the jaws to the closed or gripping position, as in Fig. 1. At the inner end of rod 44 is a head 48, which lies in a socket 49 at the rear end of the holder. A handpiece 50, pivoted in the socket, is provided with a boss or projection 51, adapted to engage head 48 when the handle is oscillated, as in Fig. 7, to force the rod and jaws forward against the power of 120 spring 47. Springs 52, which are secured to 125 the holder, bear against the rear ends of the jaws and throw them to the open or releasing position when the rod is forced forward by engagement of the boss on the handpiece

with head 48 when the handpiece is oscillated, as in Fig. 7, the forward movement of the rod, cross-piece, and jaws causing the rear ends of the jaws to ride down the beveled end 5 46 of the carrier. The instant the handpiece is moved back to its normal position, as in Fig. 1, spring 47 will move the rod, cross-piece, and jaws backward, causing the rear ends of the jaws to ride up the beveled end 10 of the carrier and throw their forward ends to the gripping position against the power of springs 52, as in Fig. 1. The handpiece is shown as provided with a lug 53, which, when the handpiece is thrown to the releasing position, as in Fig. 7, passes into a slot 55 in the rear end of the holder, serving as a guide, and with a lug 54, which when the handpiece is at the gripping position, as in Fig. 1, engages the rear end of the holder, serving as a 15 stop.

The machine is driven by means of a belt (not shown) passing over the belt-pulley, which is connected by means of clutch mechanism with gear-wheel 26, which in turn 20 meshes with pinion 30. The gear-wheel is provided with a hub 56 having a groove 57.

58 denotes a sliding clutch-dog carried by the hub, which is actuated by a spring 91 and is adapted to engage a socket 59 in the hub 25 of the belt-pulley. (See dotted lines, Fig. 1.) This clutch-dog is provided with a lug 60, which is adapted to engage an incline 61 on a shoe 62, which lies in groove 57 in the hub of the gear-wheel. (See dotted lines, Fig. 1, 30 in connection with Figs. 2, 3, and 4.) The shoe is provided with a shank 63, which extends downward into a socket 64 in the framework and is provided with a recess 65, whose lower wall is adapted to be engaged by a dog 35 66, pivoted in a recess 67 in a bell-crank lever 68, itself pivoted to the framework, as at 92, and lying partly under the rim of the belt-wheel. (See Fig. 2 in connection with Fig. 4.) A spring 69, lying in the base of socket 40 64, acts to throw the shoe upward to the engaging position, as in Figs. 2 and 3, and a spring 90 (see Fig. 4) acts to throw the bell-crank lever and dog to the raised or engaging position when part 27 of the divided shaft 45 50 is moved outward, as will be more fully explained.

70 denotes a lug seated in the framework and passing through an opening 71, which leads into recess 67 in the end of the bell-crank lever, the function of which is to engage the rear end of dog 66, that is back of the pivotal point, and tilt said dog when the bell-crank lever is swung downward, as clearly 55 shown in Fig. 4, and draw down the shoe to 60 release the sliding clutch-dog, as will be more fully explained.

In order to stop the rotation of the divided shaft the instant the predetermined number of revolutions have been completed, leaving 65 the jaws in the starting position, we provide a suitable brake, which operates in connection with gear-wheel 26. In the present in-

stance we have shown a collar 72, having a boss 73. (See Fig. 8.) The collar is rigidly secured to the gear-wheel and turns with it 70 on stud 24. A suitable pad 74, carried by a housing 75 upon the framework, is engaged by the boss on collar 72 at the end of each rotation of the collar, as clearly shown in Fig. 8. The pressure of the pad upon the 75 boss may be regulated by means of a set-screw 76 in the housing. In the side of gear-wheel 26 we provide a recess 77, which is adapted to be engaged by a hook 78 on a lever 79, which is pivoted to the framework, as 80 at 80. The engagement of the hook with the recess takes place an instant after the engagement of boss 73 with the pad and insures the stoppage of the gear-wheel, divided shaft, jaws, &c., in the exact position desired. In 85 practice the gear-wheel and pinion are so proportioned that one revolution of the gear-wheel will produce a predetermined number of revolutions of the pinion—for example, the number of teeth in the gear-wheel and the 90 pinion may be to each other as three to one or four to one, it being simply required to give to the tongs a sufficient number of revolutions to throw the surplus tin from the article they are holding.

95 81 denotes a link, one end of which is pivoted to lever 79, the other to a lever 82, which is itself pivoted, as at 83, to a bracket 84, which extends outward from the bed.

85 100 denotes a receptacle hinged, as at 86, to lever 82 and normally standing upright directly under the jaws. A spring 87 (shown as connected to lever 79 and to the bed) acts to return lever 79, the link, lever 82, and the receptacle to their normal positions and 105 retain them there. The receptacle is made of suitable shape and size to receive and retain temporarily an article dropped into it from the jaws. When lever 82 is thrown to the position shown in dotted lines in Fig. 1, as 110 will be more fully explained, the receptacle which is hinged on the side in the direction of movement of the lever will be thrown by centrifugal force from the upright to a horizontal position and will expel therefrom the 115 article that has been dropped into it from the jaws, the horizontal position of the receptacle being indicated by dotted lines in Fig. 1. On the return movement of lever 82, which 120 takes place an instant later, the lever strikes a pin 88, projecting upward from link 81, which stops the movement of the lever, and centrifugal force causes the receptacle to resume its upright position directly under the jaws, as clearly shown in Figs. 1 and 2.

125 The operation of the machine is as follows: Belt-pulley 25 is always in motion when the machine is in use. The other parts of the machine are stationary, except when in actual use. The normal position of the jaws is 130 horizontal, as in full lines in Figs. 1 and 2. Suppose the machine to have been in use and a tinned article to be held by the jaws. The operator first moves handpiece 50 from the

position shown in Fig. 1 to the position shown in Fig. 7. This movement through the engagement of boss 51 with head 48 on rod 44, which carries the jaws, moves said jaws forward, causing the rear ends thereof to ride down the beveled end 46 of carrier 45 and permitting springs 52 to throw the jaws to the open position, as in Fig. 7. This releases the article held by the jaws, which drops into the receptacle. The operator then places another article to be tinned between the jaws and moves the handpiece back to the position shown in Fig. 1. Spring 47 moves rod 44, carrying the jaws backward, and the rear ends of the jaws ride up bevel 46 at the forward end of the carrier, which throws the jaws to the closing position, as in Fig. 1, against the power of springs 52, thus gripping the article firmly, one of the jaws being of course provided with as small a contact point as possible, as at 89, but which is so shaped as to grip and hold the article firmly. The operator next still gripping the handpiece swings it upward, which swings the jaws downward into the vertical position. He next, still holding the handpiece, swings the jaws inward and downward against the power of spring-actuated pin 39, as indicated by dotted lines in Fig. 2, and dips the article held by the jaws in the molten tin in the trough. When the jaws are swung downward to dip the article, arm 33, which carries part 28 of the divided shaft, turns on its hinge, as indicated in dotted lines, the position of the parts of the shaft being clearly shown in Fig. 5. When the inner end of part 28 is swung downward and outward away from collar 31, spring 90 will act to raise bell-crank lever 68, the lower arm of which will press sliding rod 32 inward. (See Fig. 5 in connection with Fig. 4.) It has already been explained that at the end of each whirling operation the rotation of gear-wheel 36, the divided shaft, and the jaws will be stopped through the engagement of boss 73 on collar 72, carried by the gear-wheel with pad 74, after which hook 78 on lever 79 engages recess 77 in the side of the gear-wheel and locks the gear-wheel, shaft, and jaws in the normal or starting position. It should be understood that the engagement of hook 78 with the recess in the gear-wheel although positive is a light engagement, so that the first movement of the jaws and the divided shaft—that is, the oscillation of the shaft which lowers the jaws from the horizontal to the vertical position—will through the engagement of pinion 30 with the gear-wheel turn the latter slightly and throw the hook out of the recess against the power of spring 87, as clearly indicated by dotted lines in Fig. 1, which throws the receptacle and expels an article therefrom, as already explained. This oscillation of the shaft carries the gear-wheel forward in the direction of the arrow in Fig. 1 far enough to carry the recess beyond the hook, which will rest against the side of the gear-wheel ready

to engage again at the completion of the next revolution. Before the breaking of the shaft—that is, the downward movement of part 28 to dip an article—bell-crank lever 68 was in the position shown in Fig. 4, but shoe 62 was in the position shown in Figs. 2 and 3—that is, held at its extreme upward position in groove 57 by means of spring 69. The extreme up-tilted position of the bell-crank lever is not shown in the drawings, the position shown in Fig. 3 being after said lever has commenced to swing downward, and pivoted dog 66 through its engagement with recess 65 is about to draw the shoe downward, as will presently be fully explained. It will be obvious that with the bell-crank lever in the up-tilted position and the inner end of sliding rod 32 in the position shown in Fig. 5 the return of arm 33, part 28 of the shaft, and the jaws from the position shown in dotted lines in Fig. 2 to a position in which the parts of the shaft will be in alignment with each other, as in Figs. 2 and 6, the jaws, however, still being downward will force sliding rod 32 outward, as in Fig. 4, and will throw the bell-crank lever from the up-tilted position to the down-tilted position, as in Fig. 4, against the power of spring 90. As the bell-crank lever commences to swing downward, pivoted dog 66 will engage recess 65 in the shank of the shoe and will tilt said dog until the rear end thereof engages the bottom of recess 67, in which it is pivoted, as in Fig. 3, when continued downward movement of the bell-crank lever will draw the shoe downward from the position shown in Figs. 2 and 3 and in dotted lines in Fig. 4 to the position shown in full lines in Fig. 4. As the downward movement of the bell-crank lever continues, the rear end of dog 66 will engage lug 70, which projects upward into recess 67 through opening 71 and will tilt the rear end of said dog, as in Fig. 4, sufficiently to swing the forward end thereof out of recess 65 in the shank of the shoe. The instant the shoe is released by the passing of the forward end of the dog out of the recess spring 69 will again throw the shoe to the raised position, as in Figs. 2 and 3. The bell-crank lever, however, will remain in the position shown in Fig. 4 until the breaking of the shaft, as in Fig. 5, again permits spring 90 to up-tilt the bell-crank lever and force the sliding rod inward. The lower arm of the lever remains constantly in contact with the sliding rod, the outer end of which is shown as rounded, so as to reduce friction to the minimum.

The inoperative—that is, the disengaging—position of sliding clutch-dog 58 is clearly shown in Fig. 2, in which position it is retained by the shoe until the latter is drawn downward, as explained. When the jaws, arm 33, and part 28 of the divided shaft are swung downward, as in dotted lines in Fig. 2, said part 28 of the divided shaft moves outward toward the right, (see Fig. 5,) which leaves spring 90 free to up-tilt the bell-crank

lever and move the sliding rod toward the right from the position shown in Figs. 4 and 6 to the position shown in Fig. 5, the inner end of the sliding rod following part 28 of the 5 shaft and remaining in contact therewith. After the dipping operation the operator may swing part 28 of the divided shaft upward to the horizontal position or he may let go of the handpiece and leave this upward movement of the arm, jaws, and part 28 to be produced by spring-actuated pin 39. It will be obvious from Figs. 5 and 6 that this upward movement of part 28 of the divided shaft will force the sliding rod toward the left, as in 10 Fig. 4, the effect of which will be to tilt the bell-crank lever downward and cause pivoted dog 66 through its engagement with recess 65 in the shank of the shoe to draw the shoe downward, which releases sliding clutch-dog 58 and 15 permits spring 91 to throw it forward into engagement with socket 59 in the belt-pulley. The downward movement of the bell-crank lever continues until pivoted dog 66 through the engagement of the rear end thereof with 20 lug 70 is tilted sufficiently to swing the forward end of the dog out of recess 65, when spring 69 will instantly throw the shoe upward again to its normal position, as in Figs. 2 and 3, the bell-crank lever, however, remaining 25 in the position shown in Fig. 4 until it is again tilted upward by the breaking of the shaft, as already explained. The instant the sliding clutch-dog engages the recess in the belt-pulley motion is communicated to gear-wheel 26, the pinion, shaft, and jaws, and the 30 whirling operation takes place. It should be noted, however, that injury to the operator or to the machine by premature rotation of the divided shaft and jaws is rendered practically impossible, as it is the upward movement 35 of arm 33, part 28 of the shaft, and the jaws that causes the sliding rod to produce the downward tilt of the bell-crank lever, which in turn draws the shoe downward and 40 releases the sliding clutch-dog, it being noted, furthermore, that the slight rotary movement imparted to the gear-wheel by the oscillation of the jaws at the time hook 78 is disengaged from the recess in the side of the gear-wheel 45 and the article last tinned is expelled from the receptacle, stops the instant the jaws reach their downward position and is a hand movement only, the gear-wheel not being connected with the belt-pulley until the shoe is 50 drawn downward by an upward movement of part 28 of the shaft after the shaft has been broken. As already fully explained, the whirling operation is produced by a plurality of revolutions of pinion 30, which are 55 produced by a single revolution of the gear-wheel. As the gear-wheel approaches the end of a revolution lug 60 on the sliding clutch-dog comes into engagement with incline 61 on the shoe, (see dotted lines, Fig. 1,) 60 the lug riding up the incline and withdrawing the sliding clutch-dog from socket 59 in the belt-pulley. The instant this disengagement 65

is effected boss 73 on collar 72, moving with or forming part of the gear-wheel, engages pad 74, which stops the rotation of the 70 gear-wheel, pinion, divided shaft, and jaws. An instant later the gear-wheel is locked through the engagement of hook 78 with the recess in the side of the gear-wheel. This completes the operation of tinning an article. 75 The operator then opens the jaws, as in Fig. 7, which releases the tinned article, permitting it to drop into the receptacle, then places another article to be tinned between the jaws and closes the jaws by moving the handpiece 80 back to the position shown in Fig. 1, then oscillates the divided shaft to carry the jaws downward, and then breaks the shaft, swinging part 28 and the jaws downward, as before, to dip the article in molten tin in the 85 trough, the upward movement of part 28 of the shaft producing the downward movement of the shoe and causing the release of the clutch-dog and connecting the gear-wheel with the belt-pulley, as before. 90

Having thus described our invention, we claim—

1. In a machine of the character described the combination with jaws for holding an article to be tinned and a shaft by which they 95 are carried, of means for rotating the shaft whereby the jaws are whirled to remove surplus tin from the article by centrifugal force.

2. In a machine of the character described the combination with a trough for holding 100 molten tin, jaws for holding articles and a shaft by which the jaws are carried, of means for rotating the shaft whereby the jaws are whirled to remove surplus tin from articles carried thereby and a hood covering the 105 trough and the jaws which catches flying particles of tin.

3. In a machine of the character described the combination with jaws for holding an article to be tinned and a shaft by which the 110 jaws are carried, of means for rotating the shaft whereby the jaws are whirled to remove surplus tin from the article by centrifugal force, a receptacle which receives tinned articles when the jaws are opened and means for 115 removing a tinned article therefrom.

4. In a machine of the character described the combination with jaws for holding an article to be tinned and a divided shaft by which the jaws are carried, of means for connecting 120 the parts of said shaft when in alinement, means for rotating said shaft when the parts are in alinement whereby the jaws are whirled to remove surplus tin from an article carried thereby, driving mechanism, a clutch and intermediate connections whereby the clutch is 125 operated to connect the shaft with the driving mechanism when the parts of said shaft are placed in alinement after having been broken. 130

5. In a machine of the character described the combination with a shaft comprising parts 27 and 28, a hinged arm in which part 28 is mounted to rotate, bearings in which part 27

may rotate, a longitudinally-sliding rod in part 27, a pinion carried by part 27, a gear-wheel with which the pinion meshes and a driving-pulley, of a sliding spring actuated clutch-dog carried by the gear-wheel and adapted to engage the driving-pulley, a spring-actuated shoe having an incline which is engaged by the clutch-dog to retract the latter, a bell-crank lever having a pivoted dog adapted to engage the shoe and draw it downward, the other arm of said lever contacting with the sliding rod, a spring acting to uptilt the bell-crank lever and move the sliding rod inward when the shaft is broken and a lug 5 adapted to engage the rear end of the pivoted dog to tilt said dog and release the shoe at the end of the downward movement of the bell-crank lever, said downward movement of the bell-crank lever, pivoted dog and shoe 10 being produced by the outward movement of the sliding rod caused by the upward movement of part 28 after the shaft has been broken and acting to release the sliding clutch-dog, causing the latter to connect the gear-wheel with the belt-pulley.

6. In a machine of the character described the combination with jaws by which articles are carried, a shaft by which the jaws are carried and means for rotating the shaft, whereby the jaws are whirled to remove surplus tin from the articles by centrifugal force, of driving mechanism, a clutch and mechanism intermediate the shaft and the clutch for stopping and starting the machine.

7. In a machine of the character described the combination with jaws by which articles are carried, a shaft comprising two parts by one of which the jaws are carried and a trough, of driving mechanism, a clutch and mechanism intermediate the shaft and the clutch whereby when the shaft is broken as in dipping an article, the return movement to place the parts of the shaft in alinement connects the shaft with the driving mechanism and rotates the shaft to whirl the jaws.

8. In a machine of the character described the combination with jaws by which articles are carried, a shaft comprising two parts one of which carries the jaws, and a trough, of driving mechanism, a clutch, mechanism intermediate the shaft and the clutch whereby when the shaft is broken as in dipping an article, the return movement to place the parts of the shaft in alinement connects the shaft 55 to the driving mechanism and rotates the shaft to whirl the jaws and means for stopping the rotation of the shaft leaving the jaws in the starting position.

9. In a machine of the character described the combination with jaws by which articles are carried and a shaft comprising two parts, one of which carries the jaws, of driving mechanism, a clutch and mechanism intermediate the shaft and the clutch whereby 65 when the parts of the shaft are placed in alinement after the shaft has been broken, the

clutch is operated to connect the shaft with the driving mechanism.

10. In a machine of the character described the combination with jaws by which articles 70 are carried and a shaft comprising two parts one of which carries the jaws, of driving mechanism, a clutch, mechanism intermediate the shaft and the clutch whereby when the parts of the shaft are placed in alinement after the 75 shaft has been broken, the clutch is operated to connect the shaft with the driving mechanism, and means for stopping the rotation of the shaft with the jaws in the starting position.

80 11. In a machine of the character described the combination with a driving-pulley having a socket 59, a gear-wheel having a hub and a spring-actuated clutch-dog socketed in said hub and adapted to engage the socket, of a 85 spring-actuated shoe having an incline which is engaged by the clutch-dog to withdraw the latter and disconnect the gear-wheel from the driving-pulley, a two-part shaft, and mechanism intermediate the shaft and the shoe 90 whereby the placing of the parts of the shaft in alinement after the shaft has been broken retracts the shoe and releases the clutch-dog.

95 12. In a machine of the character described the combination with a driving-pulley, a gear-wheel and a spring-actuated clutch-dog carried thereby and adapted to engage the driving-pulley, of a spring-actuated shoe having an incline which is engaged by the clutch-dog to withdraw the latter, a spring-actuated 100 bell-crank lever carrying a pivoted dog adapted to engage the shoe and retract it, a lug 70 which is engaged by the rear end of the pivoted dog to tilt the latter and release the shoe, a two-part shaft, a sliding rod carried 105 by one part which contacts with the bell-crank lever and a hinged arm in which the other part of the shaft is journaled, the breaking of the shaft by movement of the arm acting to release the bell-crank lever which 110 moves the sliding rod inward, and the return movement of the arm to place the portion of the shaft carried thereby in alinement, moving the sliding rod outward again which tilts the bell-crank lever, draws the shoe downward and releases the clutch-dog.

115 13. In a machine of the character described the combination with a gear-wheel having a recess and a lever 79 having a hook adapted to engage said recess, of a shaft, a pinion carried thereby and engaging the gear-wheel, jaws also carried by the shaft, a lever 82, a receptacle hinged to said lever and adapted to receive an article from the jaws and a link connecting levers 79 and 82, the parts being 120 so arranged that oscillation of the shaft to place the jaws in the downward position will move the gear-wheel, throw the hook from the recess and also throw the receptacle and 125 expel an article therefrom.

130 14. The article-holder 29 comprising a carrier having a beveled end, a rod passing

through the carrier, jaws carried by said rod whose rear ends engage the bevel, means for opening the jaws when the rod is moved forward and a spring acting to retract the rod causing the rear ends of the jaws to ride up the bevel and throw the forward ends to the gripping position.

15. The article-holder 29 comprising a carrier having a beveled end, jaws whose rear ends engage the bevel, a rod passing through the carrier and itself carrying the jaws, a spring acting to retract the rod causing the rear ends of the jaws to ride up the bevel and throw the forward ends to the gripping position, a pivoted handpiece having a boss adapted to engage the rod and force the latter forward against the power of the spring and means for throwing the jaws to the open position when the rod is moved forward.

20. 16. In a machine of the character described the combination with a shaft comprising parts 27 and 28, an article-holder carried by part 28, a swinging arm in which part 28 is journaled, bearings for part 27 and a sliding rod 25 carried by part 27, of a driving-pulley, a clutch and mechanism intermediate the sliding rod and the clutch whereby the return of the arm to its normal position after the shaft has been broken will cause the clutch 30 to engage the driving mechanism.

17. In a machine of the character described the combination with a shaft comprising parts 27 and 28, an article-holder carried by part 28, a swinging arm in which part 28 is journaled, bearings for part 27 and a sliding rod carried by part 27, of a driving-pulley, a spring-actuated clutch-dog, a spring-actuated shoe having an incline by which the clutch-dog is retracted, a spring-actuated bell-crank 40 lever which is engaged by the sliding rod, a pivoted dog carried by the bell-crank lever, which retracts the shoe and releases the clutch-dog, and a lug by which the pivoted dog is engaged to tilt the latter and release 45 the shoe.

18. In a machine of the character described the combination with a shaft, an article-holder and a pinion carried thereby and a gear-wheel which meshes with the pinion and is provided with a recess, of a lever 79 having a hook engaging said recess, a receptacle to receive articles from the holder, a lever 82 by which the receptacle is carried and a link connecting said levers, whereby when the 50 holder is oscillated the hook will be thrown out of the recess and the receptacle will be thrown to expel an article therefrom.

19. In a machine of the character described the combination with an article-holder and a pivoted swinging arm, of a divided shaft one of whose parts is journaled in the swinging arm, the other part being mounted to be in alinement therewith when the arm is in its normal position and means for locking said 60 parts together when they are in alinement.

20. In a machine of the character described the combination with an article-holder and a pivoted swinging arm, of a divided shaft one of whose parts is journaled in the arm and the other mounted to be in alinement therewith when the arm is in its normal position and means for locking the parts of the shaft when in alinement and preventing breaking of the shaft except when the article-holder is in a predetermined position. 70

75 21. In a machine of the character described the combination with an article-holder and a pivoted swinging arm, of a divided shaft comprising parts 27 and 28, said part 28 being journaled in the arm and carrying at one end the article-holder and at the other end a collar 36 having a recess, and said part 27 carrying a collar 31, and a spring-actuated pin socketed in collar 31 and engaging the recess in collar 36 whereby the parts of the 80 shaft are locked together.

22. In a machine of the character described the combination with an article-holder and a pivoted swinging arm, of a divided shaft comprising parts 27 and 28, said part 28 being journaled in the arm and carrying at one end the article-holder and at the other end a collar 36 having a recess straight on the under side and an arc-shaped curve on the upper side, and said part 27 having a collar 95 and a spring-actuated locking-pin socketed in said collar and having its forward end shaped to correspond with the recess in collar 36, whereby the parts of the shaft are locked in alinement and breaking of the shaft 100 is prevented except when said locking-pin and recess are in a predetermined position.

23. In a machine of the character described the combination with an article-holder, a pivoted swinging arm and a spring-actuated pin 105 39 for retaining said arm at its normal position, of a divided shaft one of whose parts is journaled in the swinging arm and carries the article-holder, the other part being mounted to be in alinement therewith when the arm 110 is in its normal position, and means for locking said parts together when they are in alinement.

24. In a machine of the character described the combination with an article-holder, a pivoted swinging arm and a divided shaft one of whose parts is journaled in the swinging arm and carries the article-holder, the other part being mounted to be in alinement therewith when the arm is in its normal position 115 120 and carrying a longitudinally-sliding rod, of means for locking said parts together when they are in alinement, driving mechanism and mechanism operated by the longitudinally-sliding rod for connecting the driving 125 mechanism with the operating parts.

25. In a machine of the character described the combination with a shaft and an article-holder and a pinion carried thereby, of a gear-wheel having a recess, a brake for stop- 130

ping the rotation of the gear-wheel, a lever 79 having a hook adapted to engage the recess, a lever 82, a receptacle hinged to said lever for the purpose set forth, a link connecting levers 79 and 82 and a spring acting to throw the hook into engagement with the recess at the instant the gear-wheel stops.

In testimony whereof we affix our signatures in presence of two witnesses.

HENRY L. BRADLEY.
FREDERIC W. OTIS.
